UNITED STATES PATENT OFFICE.

OSCAR A. SMITH, OF EAST CLEVELAND, OHIO, ASSIGNOR TO THE NATIONAL ACME COMPANY, OF CLEVELAND, OHIO, A CORPORATION OF OHIO.

BINDING POST.

Application filed May 2, 1922. Serial No. 558,014.

To all whom it may concern:

Be it known that I, OSCAR A. SMITH, a citizen of the United States, residing at East Cleveland, in the county of Cuyahoga and State of Ohio, have invented certain new and useful Improvements in Binding Posts, of which the following is a specification.

This invention relates to binding posts, an object thereof being to provide an improved device of this character, which will be inexpensive, quick and easy to manufacture and efficient and serviceable in use.

A further object of this invention is to provide a binding post wherein a gripping or clamping slide is adapted to be reciprocated in a channel or slot in the body portion of the device by means of a cap, the latter being threaded to the slide and body portion by means of right and left hand threads of the same pitch whereby, upon rotation of the cap in either direction, the slide will be operated.

Other objects of this invention will appear in the following description thereof, reference being had to the accompanying drawings forming a part of this specification, wherein like reference characters indicate corresponding parts in the several views, and wherein Fig. 1 is a side elevation illustrating my improved binding post; Fig. 2 is a vertical section thereof illustrating the parts in open position; Fig. 3 is a vertical section illustrating the parts in closed position; Fig. 4 is a perspective view of the body member; Fig. 5 is a top end view thereof; and Fig. 6 is a perspective view of the slide member.

In its preferred form herein shown and described, my improved binding post comprises in general an exteriorly threaded body portion having a slot, recess or channel adapted to receive a slide member. The latter is provided with a threaded projection extending into a tapped hole in the operating cap, which is thus threaded to the body member and the slide, whereby upon rotation thereof the slide will be reciprocated.

Referring to the drawings, it will be seen that the body member of the present binding post is provided with an enlarged base 9, and a shank 10 extending therefrom and slotted to form a suitable channel or guide-

way 11 for the slide member. The binding post is adapted to be attached to any suitable support in the usual manner by means of a tapped hole 12 located in the bottom thereof. The bifurcated or slotted shank portion 10 is provided with a threaded portion 13, the threads cooperating with suitable interior threads 14 in a cap or sleeve 15.

Within the slot or channel 11 is located a gripping member or slide 16 having a width substantially the same as the diameter of the non-threaded portion of the shank 10. The end faces 17 of the slide are preferably segmental or curved so as to conform to the curvature of the shank portion 10. Extending from the slide 16 is an integral projecting member 18 of suitable length and thickness, the side faces 19 thereof being segmental or curved and provided with threads. A hole 20 is tapped into the top of the cap 15 of suitable size to receive the projecting portion 18, the thread portions of the parts cooperating with each other.

It will thus be seen that the cap 15 and body portion 10 are connected together by threaded portions 13 and 14, which are preferably right hand threads, and it will also be seen that the cap 15 and slide member 16 are connected together by means of threaded portions, preferably left hand threads. As a result therefore, the cap is connected to the body member and the slide member by means of right and left hand threads of the same pitch so that upon rotating the cap both the slide and cap will travel longitudinally over the body member, the slide however, traveling twice the distance of the cap by virtue of the right and left hand threads.

By virtue of the present invention therefore, a quick operating and gripping binding post is provided. From the positions shown in Figs. 1 and 2, where the cap and slide have been retracted to their extreme upper positions, it is merely necessary to rotate the cap 15 several turns and the slide will be carried to its lower position by virtue of the reverse threads, the slide member thus being shifted into the gripping position at twice the speed formerly necessary where the slide was secured to the cap and both were shifted the same distance together.

Thus, it will be seen that the slide mem-

ber 16 is so connected to the operating member 15, which is threaded to the body member and shiftable longitudinally thereof, that the slide will be reciprocated in the slot 5 11 upon rotation of the operating member or cap 15. Furthermore, means is provided for shiftably connecting the slide member 16 with the operating cap, in the present instance comprising the cooperating threaded 10 portions 19 and 20, so that upon shifting the operating cap longitudinally of the body member the slide will not only be held for movement therewith, but will also be shifted relatively thereto.

15 Thus it will be observed that the slide is shifted in both directions by means of the coacting threads on the cap, or sleeve, and the slide, and it is a well known fact that a thread action is a most powerful lifting 20 medium and therefore is commonly used in lifting jacks whereby many tons may be easily lifted.

Although I have described my invention in its preferred form, it is to be understood 25 that I do not limit myself to the construction herein shown and described except in so far as defined in the claims and embraced within the scope thereof.

I claim as my invention:

30 1. A binding post comprising a slotted body, a gripping slide movable in the slot of the body, and a sleeve, and means connecting the sleeve to the body and slide so that the rotation of the sleeve will cause 35 the slide to travel a greater longitudinal distance than the sleeve.

2. A binding post comprising a slotted body, a gripping slide movable in the slot of the body, and a sleeve, and means connecting the sleeve to the body and slide so 40 that the rotation of the sleeve will cause the slide to travel faster than the sleeve.

3. A binding post comprising a slotted body, a gripping slide movable in the slot 45 of the body, and a sleeve, and means connecting the sleeve to the body and slide so that the rotation of the sleeve will cause the slide to travel a greater longitudinal distance and faster than the sleeve.

50 4. A binding post comprising a slotted body, a gripping slide movable in the slot of the body, and a sleeve threaded to both the body and slide.

55 5. A binding post comprising a slotted body, a gripping slide movable in the slot of the body, and a sleeve threaded to both the body and slide by differently formed threads whereby the slide will travel faster than the sleeve.

60 6. A binding post comprising a slotted body, a gripping slide movable in the slot of the body, and a sleeve threaded to both the body and slide by right and left hand threads whereby the slide will travel a greater distance than the sleeve.

7. A binding post comprising a slotted body having exterior threads, a reciprocating slide in the slot of the body and having an exteriorly threaded portion, a rotatable cap threaded on to the body by one kind of thread and on to the slide by a different kind of thread. 70

8. A binding post comprising a slotted body having exterior threads, a reciprocating slide in the slot of the body and having an exteriorly threaded portion, a rotatable cap threaded on to the body by one kind of thread and on to the slide by a different kind of thread, said threads having the same pitch. 75

9. A binding post comprising a slotted body having exterior threads, a reciprocating slide in the slot of the body and having an exteriorly threaded portion, and a rotatable cap threaded on to the body and slide by right and left hand threads. 80

10. A binding post comprising an exteriorly threaded slotted body, a reciprocating slide in the slotted body and having an exteriorly threaded portion, an interiorly threaded cap cooperating with the threads of the body and having above the body an interiorly threaded portion cooperating with the exteriorly threaded portion of the slide. 85

11. A binding post comprising an exteriorly threaded slotted body, a reciprocating slide in the slotted body and having an exteriorly threaded portion, an interiorly threaded cap cooperating with the threads of the body and having above the body an interiorly threaded portion cooperating with the exteriorly threaded portion of the slide, said cap enclosing only the outer end of the slot. 100

12. A binding post comprising an exteriorly threaded slotted body, a reciprocating slide in the slotted body and having an exteriorly threaded portion, an interiorly threaded cap cooperating with the threads of the body and having above the body an interiorly threaded portion cooperating with the exteriorly threaded portion of the slide, said cap enclosing only the outer end of the slot, the threads between the cap and body and the cap and slide having a different formation whereby the travel of the slide will be greater than that of the cap. 105

13. A binding post comprising a slotted body member, a slide carried in the slot thereof, and an operating sleeve encircling and shiftable longitudinally of said body member and having means for shifting the slide relatively quicker than the longitudinal movement of said operating sleeve. 110

14. A binding post comprising a slotted body member, an operating sleeve encircling and shiftable longitudinally thereof, a slide shiftable in the slotted body member, and 115 120 125 130

means carried by the body, operating sleeve and slide for shifting said slide relatively faster than said operating sleeve.

15. A binding post comprising a slotted body portion, a rotatable operating sleeve encircling and shiftable longitudinally thereof, a slide shiftable in said slotted body portion and differently formed thread-

ed means connecting the operating sleeve with the body and slide for effecting a faster 10 reciprocating movement of the slide than the longitudinal movement of the operating sleeve.

Signed at Cleveland, Cuyahoga County, Ohio, this 27th day of April 1922.

OSCAR A. SMITH.
